S. D. HALLEY.
Combined Square, Protractor, &c.

No. 223,727. Patented Jan. 20, 1880.

UNITED STATES PATENT OFFICE.

SAMUEL D. HALLEY, OF ST. LOUIS, MISSOURI, ASSIGNOR OF ONE-HALF OF HIS RIGHT TO WILLIAMS DAMAN, OF SAME PLACE.

COMBINED SQUARE, PROTRACTOR, &c.

SPECIFICATION forming part of Letters Patent No. 223,727, dated January 20, 1880.

Application filed December 6, 1879.

To all whom it may concern:

Be it known that I, SAMUEL D. HALLEY, of St. Louis, Missouri, have invented a new and useful Combined Square, Protractor, Pitch-Board, Trammel, Level, and Rule, of which the following is a full, clear, and exact description, reference being had to the annexed drawings, making part of this specification, in which—

10 Figure 1 is a plan or face view of the instrument, the parts being arranged to form a T-square; Fig. 2, a similar view, but showing the parts as in a protractor. Fig. 3 shows the parts arranged to form a carpenter's square, Fig. 4 as a shoulder-square, Fig. 5 as a pitch-board; Fig. 6, a sectional view, showing the screws used in attaching the rule or straight-edge to the triangle and the parts immediately therewith connected; Fig. 7, a detail 15 showing the pencil-holder in the outer end of the rule; and Fig. 8, an edge elevation of the plumb-bob.

The same letters denote the same parts.

The present invention can be used as a T-square, a shoulder-square, an ordinary square, a protractor, a pitch-board, a trammel, a level, and a rule, making it a convenient instrument for carpenters, architects, draftsmen, and others.

30 Referring to the drawings, A represents a triangle, having the angle a a right angle and the other two, a' a'' , angles of forty-five degrees each. B represents an arm, straight-edge, or rule, connected with the triangle by means of the screws C and D.

The triangle is slotted at a^2 , a^3 , and a^4 . The slot a^2 is parallel with the side a^5 of the triangle, and at the end toward the angle a is extended, as shown at a^6 , Fig. 5. The slot a^3 is 40 parallel with the side a^7 of the triangle, and near the angle a' it connects with the slot a^4 . The latter is parallel with the side a^8 of the triangle, saving at its ends a^9 and a^{10} , and at its center a^{11} it is shaped as seen more distinctly in Fig. 5.

45 The arm B has a slot, b, extending longitudinally therein. The edge b' of the slot is taken as the longitudinal axis of the arm. At its ends the slot is extended, as shown at b^2 b^3 , Fig. 5, and the edge b' is notched at b^4 , b^5 , and b^6 .

Now, to form a T-square, the arm B is placed as in Fig. 1—that is, the extension b^2 of the slot b coincides with the extension a^6 of the slot a^2 , and the arm is moved until the 55 screw D enters the notch a^{11} . The screws C and D are then tightened. The side a^9 of the triangle then becomes the edge to apply to the work.

When used as a protractor, the points b^2 and a^6 are kept in coincidence and the arm is turned to the desired angle. For this purpose the triangle is provided with an angle-scale, a^{12} , and the position of the arm B is determined by bringing the edge b' over the 60 proper line on the scale, the center of the latter being the center of the extension a^6 . The screws C D can be used to clamp the arm, as before.

To form the ordinary square the arm B is 70 swung around and fastened as in Fig. 3. In this the points b^2 and a^6 coincide, and the screw D passes through the notch b^6 .

To form a shoulder-square the arm B is moved into the position shown in Fig. 4—that 75 is, the arm B is placed so that its edge b^7 coincides with the edge a^7 of the triangle, and the screw D passes through the extension b^3 and slot a^3 , and the screw C through b^6 and a^6 , and the screws are then tightened. The side 80 a^5 of the triangle then forms the shoulder of the square.

As a pitch-board, miter, or bevel, the arm B is moved as in Fig. 5, the rise and tread of the stairs, for instance, being laid off upon 85 the edges a^5 and a^7 respectively.

As a trammel, the point e, with which the screw C is provided, is placed upon the center or initial point, and a pencil-point, pen, or cutter-wheel, e and e', respectively, is, by means 90 of the holder E, held in a perforation, e'', in the outer end of the arm B. The arm B, having the screw C in the extension b^2 , can then be used to lay off a circle from the point upon which the screw C rests.

To enable the instrument to be used as a level, the triangle A is provided with a plumb-bob, F, which is pivoted to the triangle at f. The triangle is also furnished with a scale, f', having marks f^2 f^3 . The point f^2 is in a line 100 drawn from the pivot f perpendicularly to the side a^5 of the triangle, and the point f^3 is

in a line drawn from the pivot f' perpendicularly to the side a^7 of the triangle; then, by placing the side a^5 or the side a^7 , as the case may be, the level can be found in the usual way. The scale f'' may be graduated to enable the triangle to be turned to bring the side a^5 or a^7 to any desired angle with the center line. The arm B is graduated at G to enable it to be used as a rule. The edges of the triangle are also graduated. The bob F is forked at its point f^5 , to engage with and move upon the scale f' , and thereby be kept from dropping away from the triangle as the latter is turned upon its side. The scale f' is marked at f^4 , midway between the points f^2 f^3 , to enable, in leveling, the side a^5 of the triangle to be applied to the under side of the surfaces to be leveled. The point c of the screw C is adjustable therein, and when needed for use can be screwed to project from the screw, as in Fig. 6.

The instrument can also be used as a gage, as follows: Let the parts be as in Fig. 1, and insert a pencil, e, or cutter e' in the perforation e^2 of the arm B. The side or shoulder a^8 of the triangle is then moved along the initial line or edge to be gaged from, and the pencil or cutter lays off the desired mark or groove. The triangle A is provided with a flange, a^{13} , Fig. 6, to raise the central portion of the triangle sufficiently for the projections upon the under side thereof to clear the surface upon which the triangle may be resting.

I claim—

1. The combination of the triangle A, having the slots a^2 a^3 a^4 , extended and shaped as described, the arm B, having the slot b, extended as described, and having the notches b^4 b^5 b^6 , and the screws C and D, substantially as described. 35

2. The combination of the triangle A, having the slot a^2 , extended at a^6 , and the slot a^4 , notched or bent at a^{11} , the arm B, having the slot b, and the screws C and D, substantially as described. 40

3. The combination of the triangle A, having the slot a^6 and scale a^{12} , the arm B, having the slot b and edge b', arranged as described, and the screws C and D, substantially as described. 45

4. The combination of the triangle A, having the slots a^6 and a^4 , the arm B, having the slot b, notched at b^5 , and the screws C and D, substantially as described. 50

5. The combination of the triangle A, arm B, screws C and D, and point e, and holder E, having a pencil or wheel, substantially as described. 55

Witness my hand this 29th day of November, 1879.

SAMUEL D. HALLEY.
